CLAIM

The ornamental design for a display screen with an animated graphical user interface, as shown and described.

DESCRIPTION

FIG. 1 is a front view of a display screen with an animated graphical user interface showing a first image of a sequence; FIG. 2 is a second image thereof; FIG. 3 is a third image thereof; FIG. 4 is a fourth image thereof; FIG. 5 is a fifth image thereof; FIG. 6 is a sixth image thereof; FIG. 7 is a seventh image thereof; and, FIG. 8 is an eighth image thereof.

The three outer-most broken line rectangles showing an electronic device in the FIGURES are included for the purpose of illustrating environmental structure; the inner-most broken line rectangle showing a display screen as well as the broken lines showing portions of the graphical user interface in the FIGURES are included for the purpose of illustrating portions of the article; all broken lines form no part of the claimed design. The appearance of the transitional image sequentially transitions between the images shown in FIGS. 1-8. The process or period in which one image transitions to another image forms no part of the claimed design.

1 Claim, 8 Drawing Sheets
